INVENTOR

Charles E. Napp

UNITED STATES PATENT OFFICE.

CHARLES E. NAPP, OF LOS ANGELES, CALIFORNIA.

TELEPHONE-DIRECTORY.

1,193,590.

Patented Aug. 8, 1916.

Specification of Letters Patent. Application filed June 1, 1915. Serial No. 31,355.

To all whom it may concern:

Be it known that I, CHARLES E. NAPP, a citizen of the United States, residing at Los Angeles, in the county of Los Angeles and State of California, have invented a new and useful Telephone-Directory, of which the following is a specification.

This application is intended to cover an improvement in telephone directories, of the class shown, described and claimed in my patent issued December 10, 1907, No. 873,259.

The object of my invention is to provide a simple and convenient device which combines a telephone directory; calendar; memorandum pad and pencil holder, for use upon a desk in connection with a telephone; and my invention consists of the novel features herein shown, described and claimed.

The accompanying drawings illustrate the invention, in which—

Figure 1 is a side elevation of my telephone directory, looking in the direction of the arrow 1 in Fig. 2. Fig. 2 is a front elevation, as seen looking in the direction of arrow 2 in Fig. 1. Fig. 3 is a plan view of the base and supporting frame, the calendar plate and index cards being removed. Fig. 4 is a detached plan view of the calendar plate, as seen looking from the under side. Fig. 5 is an enlarged vertical sectional detail view taken upon the lines 5—5 of Figs. 2, 3 and 6. Fig. 6 is an enlarged horizontal sectional view taken upon the line 6—6 of Fig. 5. Fig. 7 is an enlarged fragmentary detail of the hollow hinge pindle and hinge members, as seen looking in the direction of arrow 7 in Fig. 6. Fig. 8 is a perspective view of the hollow hinge pindle.

Referring more particularly to the drawings, 1 in a general way designates the supporting frame, which is stamped from thin sheet metal and comprises the base plate 2, which supports the memorandum pad, and the index supporting plate 3. Supporting legs 4 and 5 are struck from the plate 2 and extend downwardly so that said base plate rests upon these legs at one end and upon the foot 6 thereof at the other end thereby causing said plate to stand at an angle to facilitate writing. The index supporting plate 3 is formed integral with the plate 2 and stands at an angle of 60 degrees. Hinge members are struck from the lower end of the plate 3 and bent to form loops 7 and 8. Index fingers 9 and 10 are struck from the lower end of said plate 3 and are

concentric with the hinge members 7 and 8. The index cards 11 are placed upon these fingers and rest against the plate 3, the tabs 12 thereof, extending upwardly a distance 60 above said plate so that they may be conveniently selected.

The calendar plate 13 is provided with hinge members 14 and 15 to register with the members 7 and 8 of the plate 3 and a hollow hinge pindle 16 extends through said hinge members and serves to hold the plate 13 hingedly secured to the plate 3. Slots 17 and 18 are formed in the lower end of plate 13 for the reception of the fingers 9 and 10 so that said plate may rotate around said fingers.

The pindle 16 is a hollow cylinder and is provided with a longitudinal slot 19 extending from one end thereof to near the center and ending in a transverse notch 20. The outer end of said pindle is provided with a tongue 21 adapted to engage in notches 22 in the hinge member 14. One end of a coil spring 23 engages in the notch 20 in said pindle 16 and encircles the pindle and extends outwardly through an opening 24 in the plate 3. Said spring tends to normally hold the calendar plate 13 closed. The calendar cards 25 are held in place upon the calendar plate by fingers 26 struck up from the plate 13. The memorandum pad rests upon the plate 2 and is adapted to be engaged by hooks 28 struck up from the plate 2 and is held from lateral movement by the flanges 29 and 30 formed upon the sides of the plate 2. A loop 31 is formed at one side of the plate 3 for the reception of a pencil 32 said pencil resting upon an ear 33. A hook 34 is secured to the back of the plate 3 for the reception of memoranda which is of importance.

In assembling the parts the pindle 16 is inserted through the hinge member 14 upon the plate 13, and hinge member 7 of the plate 2; then the spring 23 is inserted upon the pindle with one end engaging in the notch 20. Then the pindle is inserted through the hinge members 8 and 15. The other end of the spring is inserted through the opening 24 in the plate 3. A screw driver slot 35 is formed in one end of the pindle 16, so that when said pindle is in place and the spring hooked in the notch 20, the pindle may be rotated to tighten the spring 23. When it is tightened to the desired extent, the lip 21 upon the pindle is

allowed to engage one of the notches 22 in the hinge member 14, so that the tension of the spring tends to normally hold the calendar plate 13 closed against the index cards.

It is obvious that many changes may be made in the details of construction, without departing from the spirit of my invention, as set up in the following claims.

10. What I claim and desire to secure by Letters Patent of the United States is:

1. A telephone directory comprising a base plate, an index supporting plate formed integral with the base plate, index fingers 15 formed upon said index supporting plate and adapted to extend through a set of index cards so as to hold said cards on said plate, a calendar plate hingedly secured to said index plate, a calendar on said calendar plate, and means for normally holding said calendar plate closed against said index cards.

2. A telephone directory comprising a base plate adapted to support a memorandum pad, an index supporting plate formed integral with the base plate and adapted to support a set of index cards, hinge members upon said index plate, a calendar plate, hinge members on said calendar plate adapted to register with the hinge members on said index plate, a pintle extending through said hinge members and a spring attached to said pintle and said index plate to normally hold the calendar plate against the index cards.

3. A telephone directory comprising a base plate, an index supporting plate formed integral with said base plate, index fingers upon the supporting plate adapted to extend through a set of index cards, hinge members upon said supporting plate, a calendar plate, hinge members on said calendar plate, registering with the hinge members on said supporting plate, a pintle extending through said members and a spring attached to said pintle, and means for adjusting the tension of said spring.

4. In a telephone directory, comprising a base plate, an index supporting plate formed integral therewith, index fingers upon said

supporting plate and adapted to extend through a set of index cards to support said cards on said supporting plate, hinged members formed integral with said supporting plate, a calendar plate, hinged members on 55 said calendar plate registering with the hinged members on said supporting plate, a pintle extending through said hinged members and a spring attached to said pintle for normally holding said calendar plate against 60 said index cards.

5. A device of the character disclosed comprising a base, said base being adapted to support a writing pad, a supporting plate forming part of said base and extending 65 upwardly from said base, fingers stamped out of said supporting plate adapted to extend through a set of index cards to support said cards on said plate and to permit said cards to be swung down from said plate so 70 that the respective cards may be read, hinge members stamped out of said supporting plate, all of the above specified parts being stamped out of a single piece of sheet metal, a calendar plate, hinge members on said 75 calendar plate registering with the hinge members on said supporting plate, a pintle extending through said hinge members, a spring adapted normally to hold said calendar plate against said index cards and lugs 80 on said calendar plate for holding a calendar on said plate.

6. A device of the character disclosed comprising a base, said base being adapted to support a writing pad, a supporting plate 85 forming part of said base and extending upwardly from said base, fingers stamped out of said supporting plate adapted to extend through a set of index cards to support said cards on said plate and to permit said cards 90 to be swung down from said plate so that the respective cards may be read, all of said parts being stamped out of a single piece of sheet metal, and means for normally maintaining said index cards in superimposed position on said supporting plate.
